UNITED STATES PATENT OFFICE.

JOSEPH HUNTER DICKINSON, OF CRANFORD, NEW JERSEY, ASSIGNOR TO THE AEOLIAN COMPANY, A CORPORATION OF CONNECTICUT.

PHONOGRAPH AND THE LIKE.

1,242,155.

Specification of Letters Patent.

Patented Oct. 9, 1917.

Application filed February 10, 1916. Serial No. 77,444.

To all whom it may concern:

Be it known that I, JOSEPH HUNTER DICKINSON, a citizen of the United States, residing at Cranford, in the county of Union and State of New Jersey, have invented certain new and useful Improvements in Phonographs and the like, of which the following is a specification.

My present invention relates to improvements in phonographs and the like and more particularly relates to means for automatically controlling the lighting of the record playing compartment of the cabinet from the opening and closing of the lid. The advantages of this and other improvements forming the subject of my present invention will be apparent to those skilled in the art from an understanding of the following description in connection with the drawings.

In the drawings, Figure 1 is a fragmentary plan view of the record-playing compartment of a phonograph cabinet embodying my improvements, the lid not being shown. (In Fig. 1 the top of the figure is the back of the cabinet to which the lid is hinged; whereas the front of the cabinet is broken away.) Fig. 2 is a front to back vertical section through the left hand portion of the cabinet of Fig. 1 looking toward the left. The lid of the cabinet is shown in this view propped up in its open position. Fig. 3 is an enlarged detail of a portion of Fig. 2; Fig. 4 is a vertical section on the line 4—4 in Fig. 3 looking in the direction of the arrows; and Fig. 5 is an enlarged vertical sectional view of the lamp, light shield and reflector shown also at the right in Fig. 1, partly in horizontal section and plan.

Describing now the specific embodiment of my invention shown in the drawings:—1 is the body portion of the phonograph cabinet, 2 its lid hinged to the body at 3. (Fig. 2.). 4 is the board or deck forming the bottom of the record playing compartment wherein are located the record-supporting turn-table 5, the tone-arm 6 and sound-box 7. At the left (see Fig. 1) this board has an opening through it covered by a slotted plate 8 (compare Fig. 2) through which works the lid-top 9. The plate 8 has a side portion 8^a (compare Fig. 4) bent downwardly therefrom to which two parts

10 and 11 are screwed or riveted, these parts being preferably made of wood, fiber, hard rubber or other noise-deadening material 55 when operated against or struck by the lower end of the prop 9 as will hereafter appear.

The upper end of the prop 9 is pivoted at 12 to a bracket 13 secured to the inside of the hollow lid 2,—see Fig. 2. The parts 10 and 11 are spaced apart and so shaped as to provide an irregularly shaped passage 14 between them,—see Figs. 2 and 3. The lower end of the prop 9 (Figs. 2 and 4) has a transverse pin 15 therein which passes 65 through said passage 14 in the operation of the prop. Thus as the lid 2 is raised, the prop 9 of course lifts with it and its pin 15 follows up the inclined side 11^a of the part 11 which guides it into the mouth—or front-end (Figs. 2 and 3) of the passage 14. Continued lifting of the lid and prop, carries the pin 15 up into the passage 14 until it strikes against the depending projection 16 (Fig. 3) on the part 10. This notifies the operator 75 that the lid has been fully raised. Upon releasing the lid, it drops slightly carrying the pin down into the notch or fork 17 (Fig. 3) of the part 11 which thereupon supports the prop and lid in raised position. To lower 80 and close the lid, the operator first lifts it slightly and then lowers it into shut position. The first or lifting step carries the pin 15 upwardly out of the fork and rearwardly until it strikes against the projection 18 (Fig. 3); and the second or lowering step carries the pin downwardly out of the rear or delivery-end of the passage 14 85 and thence downwardly within the cabinet to the full extent to permit the shutting of 90 the lid. On reopening the lid, the pin 15 follows through the same cycle just described, first following up the incline 11^a and so on. The purpose of the inclined tail-piece 11^a is to compel the pin to traverse the 95 passage 14 as described instead of in the reverse direction.

This completes the description of the lid-prop illustrated but it will be understood that this specific form of the prop is not 100 essential to my invention. Proceeding now with the description of my invention:—19 is an electric-light bulb in a socket 20 mounted on the deck 4 (compare Fig. 5) at

the right side in Fig. 1. This socket is wired to the source of current supply (not shown) through an electric switch 21 mounted under the deck 4 in position to be operated by the lid-prop. The switch may be of any suitable type. 22 is its operating plunger. 23 (Fig. 2) is a lever centrally pivotally supported at 24 from the deck 4. The illustrated lever 23 consists of a metal strip having a laterally extending lug 23^a underlying one end of the prop-pin 15 when supporting the lid in elevated position by resting in the fork 17 (Fig. 3) as in Fig. 2. The opposite end 23^b (Fig. 2) of the strip 15 23 is twisted into a horizontal plane and provided with a hole through which the plunger 22 projects. The plunger is there screw-threaded and a pair of hemispherical nuts 25—25 engage these threads on opposite sides of the end 23^b of the lever and form a pivotal (yet adjustable) operating connection between said lever and the plunger of the switch. The arrangement is such that when the lid is in its propped-open position of Fig. 2, said prop not only supports the lid but also bears down on the lever 23 and pulls out the plunger of the switch which then connects the lamp 19 with the current-source. Thus raising the lid 30 into propped-position automatically lights the lamp. On the other hand the act of releasing the prop to lower the lid, automatically extinguishes the light long before the lid is closed, so that the operator has the satisfaction of knowing that the light is out and is not indefinitely consuming current while the lid is closed. Thus 26 is a spiral spring connected under tension to the lever 23 so as to force the switch-plunger 22 in 40 the direction of cutting off the current the moment the prop-pin 15 is lifted off the lug 23^a (Fig. 4 and Fig. 2) of the lever 23 as described.

Finally it will be noted that a combined eye-protector and reflector 27 is provided in connection with the electric lamp 19 shown as consisting of a preferably metal tube with bright reflecting interior having its upper end closed so that the light cannot 45 shine up directly into the eyes of the operator leaning over the record-playing compartment of the instrument. A horizontally elongated portion is removed from the side of the tube sufficient to throw the light 50 simultaneously on the sound-box in its record-playing positions as well as on the needle-tray or receptacles 28. This directs the light first where it is wanted—either to get a new needle, or to apply it to the sound-box, or to adjust the latter to the beginning 55 of the record-groove, or to the end thereof as a preliminary to the setting of an automatic stop.

Further the reflector is preferably rota-

tably adjustable about its vertical axis to 65 permit the desired lateral adjustment of the beam of light.

What I claim is:—

1. In combination, a phonograph cabinet having an interior deck and a movably connected lid, a prop for said lid connected to the same to move therewith, electric light means for lighting the interior of said cabinet, and means located below said deck and operated by the movement of said prop 70 into lid-supporting position to automatically switch on the light-means.

2. In combination, a phonograph cabinet having an interior deck and a movably connected lid, a prop for said lid connected to the same to move therewith, electric light means for lighting the interior of said cabinet, and means located below said deck and operated by the movement of said prop 75 into lid-supporting position to automatically switch on the light-means and otherwise to switch it off.

3. In combination, a phonograph cabinet having an interior deck and a movably connected lid, a prop for said lid connected to the same to move therewith, electric light means for lighting the interior of said cabinet, and a switch located beneath said deck for connecting and disconnecting the light-means to and from the current, said 80 switch being normally in disconnecting condition, and being shifted into connecting condition by the movement of the prop into lid-supporting position.

4. In combination, a phonograph cabinet 100 having an interior deck and a movably connected lid, a prop for said lid connected to the same to move therewith, electric light means for lighting the interior of said cabinet, a switch located beneath said deck 105 for connecting and disconnecting the light-means to and from the current, and means connected with said switch and caused to be pressed in one direction to operate the switch, by the movement of said prop into 110 lid-supporting position.

5. In combination, a phonograph cabinet having an interior deck and a movably connected lid, a prop for said lid connected to the same to move therewith, electric light 115 means for lighting the interior of said cabinet, a switch located beneath said deck for connecting and disconnecting the light-means to and from the current, means connected with said switch and caused to be 120 pressed in one direction to operate the switch, by the movement of said prop into lid-supporting position, and means which when not opposed by the prop operates the switch reversely.

6. In combination, a phonograph having an interior deck and a movably connected lid; a member connected to the lid to move there-

with, and working through an opening in said deck; electric light means for lighting the interior of said cabinet; a switch for connecting and disconnecting the light means to and from the current, said switch being located below said deck; and means operated by the movement of said member

with said lid when the latter is moved into open position to close said switch.

In testimony whereof, I have signed my ¹⁰ name to this specification, this 9th day of February, 1916.

JOSEPH HUNTER DICKINSON.

It is hereby certified that in Letters Patent No. 1,242,155, granted October 9, 1917, upon the application of Joseph Hunter Dickinson, of Cranford, New Jersey, for an improvement in "Phonographs and the Like," errors appear in the printed specification requiring correction as follows: Page 1, line 50, for the compound word "lid-top" read *lid-prop*; page 2, line 124, claim 5, for the word "crop" read *prop*; and that the said Letters Patent should be read with these corrections therein that the same may conform to the record of the case in the Patent Office.

Signed and sealed this 29th day of January, A. D., 1918.

[SEAL.]

R. F. WHITEHEAD,

Acting Commissioner of Patents.
